CHILD'S BED

Colleen Roberson Scoggins, Ranger, Tex.

Application August 31, 1955, Serial No. 37,730

Term of patent 7 years

(Cl. D5—4)

In the drawing, the single figure is a front perspective view of a child's bed, showing my new design.

The portion of the bed depicted in broken lines is for illustrative purposes only.

The essential features of the design are shown by means of full lines in the drawing.

I claim:

The ornamental design for a child's bed, as shown and described.
